UNITED STATES PATENT OFFICE.

ALBERT LATHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR SETTING LACING-HOOKS AND THE LIKE.

1,207,057.

Specification of Letters Patent.

Patented Dec. 5, 1916.

Application filed November 13, 1909. Serial No. 527,869.

To all whom it may concern:

Be it known that I, ALBERT LATHAM, a citizen of the United States, residing at Beverly, in the county of Essex and State of Massachusetts, have invented certain Improvements in Machines for Setting Lacing-Hooks and the like, of which the following description, in connection with the accompanying drawings, is a specification, like reference characters on the drawings indicating like parts in the several figures.

This invention relates to machines for setting simultaneously a plurality of fasteners in sheet material and more particularly to machines for setting lacing hooks or the like in the uppers of boots and shoes, although certain features of the invention may be advantageously embodied in machines for setting fasteners other than lacing hooks, for example eyelets or rivets, or in machines for setting fasteners one at a time.

It is an object of the present invention to provide a gang fastener-setting machine, having a wide range of adaptability for operating on work of various shapes and sizes, which may be used successfully by a comparatively unskilled operator, and with this end in view the invention contemplates a machine of such general arrangement that the operator's duties shall be reduced to the simplest mechanical operations, such as setting a graduated disk to adjust the machine to the work in hand, placing the work in the machine, and depressing a treadle to set the machine in motion.

More specifically it is an object of this invention to provide a machine of the class described, having a plurality of setting instrumentalities adjustably mounted therein, together with mechanism for shifting such instrumentalities for adjustment and guiding them in accordance with a predetermined curve, corresponding to the curve on which the fasteners should be set, and with simple means, such as a graduated disk, for actuating the shifting mechanism.

In dealing with tubular fasteners, such as lacing hooks, it is desirable to punch holes in the work for the reception of the fasteners which are to be subsequently inserted and set in the work. It is therefore necessary to punch the holes spaced from each other and spread from the edge of the work in correspondence with the spacing

and spread of the setting instrumentalities. The present invention, accordingly, contemplates a fastener-setting machine in which a plurality of punches, corresponding in number with the setting instrumentalities, are arranged for adjustment in a definite relation with the setting instrumentalities.

An important feature of the invention, whereby this adjustment is effected, consists in mounting setting dies and punches upon opposite ends of adjustably mounted spindles and in providing mechanism for moving the spindles in conformity to the curve on which the fasteners should be set.

Another feature consists in providing bearing members on each end of the spindles which members are adapted to slidably engage the opposite faces of a frame and receive the pressure imparted to the punches and sets during the punching and setting operations. This arrangement is particularly advantageous because it relieves the spindles of the working pressure so that they can be moved for adjustment by relatively light mechanism.

Another feature of the invention lies in the construction and arrangement of the mounting for the spindles. Preferably the spindles may be slidably mounted in pivoted frames and held yieldingly against an interchangeable outline device in such a manner that the punches and setting dies are found always on the proper curve regardless of the adjusted position of the spindles. By substituting other outline devices having different contours, the curve on which the punches and setting dies are located may be varied to suit the requirements of the work.

Other features of the invention lie in the mounting for the spindle-frames and in the mechanism for swinging the spindle-frames laterally for spacing the punches and sets. It is necessary from time to time to vary the number of fasteners being set by the machine and in a preferred embodiment of the present invention this is done by removing one or more spindle-frames and the corresponding punch and setting die. To this end the spindle-frames are forked at their rear ends and held in yielding engagement with their respective pivots. For spreading the spindle-frames to space them, each frame is provided with a cam connection to a common drum by the rota-

tion of which spreading is effected, and the arrangement is such that on the removal of a common retaining means, such as a face plate, any of the frames may be disengaged both from their spindles and from the adjusting drum. Preferably the drum may be rotated by a graduated disk, as already suggested in connection with the mechanism for shifting the setting instrumentalities.

10 Another important feature of this invention, relating to the general arrangement of fastener-setting machines, consists in the combination of vertically stationary punches and setting dies with vertically movable means for presenting the work to the punches for punching and other means for presenting fasteners to the work and to the setting devices.

Means for presenting the work to the punches may preferably comprise a piercing or punching table upon which the work is to be placed before the machine is set in operation, together with mechanism for moving the table vertically to force the work against the punches. An edge gage having an outline corresponding with the average contour of work to be operated upon may be located on the work table, and by the aid of this gage, the work may be properly located with respect to the punches. In this connection, an important feature of the invention consists in providing means movable toward the edge gage for engaging the work and drawing it up to the gage which provision takes care of slight differences in outline and insures continuous contact with the gage. Preferably such means may comprise a plurality of independent resilient fingers for engaging the work in combination with an adjusting device for regulating their pressure on the work during the drawing operation.

Still another feature of the invention relates to an end gage for engaging the end edge of the work, or the top edge thereof, in case the quarter of a shoe is being operated upon. In a preferred embodiment of my invention, this gage is mounted for lateral adjustment simultaneously with the spindle-frames so that the outer punch of the gang bears a definite relation to the gage regardless of its adjusted position. Preferably the end gage may be mounted in rigid relation with the outer punch so that the distance from the end or top edge of the work will be constant in all adjusted positions of the punches. The invention further contemplates provision for independent adjustment of this gage relative to the outer punch for varying the distance between the top or end of the work and the uppermost hole.

Still another feature in the construction of the end gage lies in mounting the gage for yielding vertical movement so that it

may constantly engage the surface of the punching table, yielding upwardly as the table is elevated for the punching operation. This arrangement effectually prevents the possibility of the work slipping under the end gage and so becoming improperly located with respect to the punches.

Other important features of the present invention relate to the means for presenting the fasteners to the work and for clenching them in cooperation with the adjustable setting dies above discussed. In this connection the invention contemplates the provision of a carrier for fasteners arranged as a continuation of the raceway, and having in combination therewith, means for positioning the fasteners on the carrier in alignment with the previously adjusted setting dies.

As embodied in a machine for setting lac-ing hooks, the hook carrier may comprise a reciprocatory head having pivoted thereto an anvil, conforming in contour with the outline device previously described in connection with the punch and die-carrying spindles and interchangeable for anvils of different contours in accordance with the interchangeable outline devices. To this anvil the hooks are carried by a novel feeding mechanism to be more particularly described hereinafter. The means for positioning the hooks in alignment with the setting dies, preferably comprise a plurality of resilient engaging fingers having ends shaped for interlocking engagement with the hooks upon the anvil, and mechanism for advancing said fingers to engage the hooks and subsequently spreading the fingers to move the hooks into alignment with the upsetting dies. The feature of the invention which consists in shaping the hook-engaging members for positive interlocking engagement with the heads of the hooks is of great importance, since, owing to the fact that the hooks are likely to vary more or less in their dimensions and to require varying degrees of force to slide them upon the anvil, it is essential that each hook shall be positively and independently handled.

Those features of the invention which relate to the mechanism for advancing and spreading the fastener-engaging members, consist in providing guides respectively in each of which one of said members is slidably mounted; in providing a single device, preferably a reciprocatory plate connected with each of the fastener-engaging members, for simultaneously advancing or retracting said members; and in providing a common drum having cam connection with each guide for spreading the guides varying distances in accordance with the position of the previously adjusted setting dies.

Another important feature of the inven-

tion consists in so coördinating the spreading mechanism for the fastener-engaging members with the adjusting mechanism for the punch and set-carrying spindles, that, 5 after engaging the separate fasteners, the fastener-engaging fingers shall be spread to move the fasteners into alignment with the previously adjusted setting dies in whatever position the latter may be. As herein shown this is effected by arranging the drum, above-mentioned, to be rotated automatically varying degrees dependent upon the position of the controlling means for actuating the spindle shifting mechanism, 10 which controlling means, as already stated, may comprise a graduated disk. It is believed that such construction is broadly new and that heretofore the combination which includes manually operated adjusting or 15 controlling means for a gang of setting dies and automatically acting mechanism for causing the fasteners to be spaced in accordance with the previous setting of the dies of said gang has never been employed.

20 That feature of the invention which relates to a novel feeding mechanism for moving fasteners from the raceway to the anvil, consists in providing an intermittently operated fastener-supplying device having an actuator constructed and arranged to be automatically thrown into and out of operation at the proper points in the cycle of the machine. As herein shown, this device comprises belt-carried brushes which extend into the path of fasteners standing in the raceway, and the operation of the actuator is so timed that this feed belt may act upon the fasteners as they are allowed to descend the raceway, first to group the 25 fasteners in line behind a stop at the end of the raceway and then to sweep them forwardly to a predetermined position on the anvil. In this connection an important feature of the invention consists in the combination of a feed belt of the type described with a reciprocatory fastener-carrier arranged to stand in operative relation with said feed belt in its initial or fastener-receiving position.

30 The present invention contemplates, as an important feature, a let-off mechanism of variable capacity whereby fasteners may be fed in groups of the proper number to the feed device above referred to and to the carrier. This mechanism may be preferably associated with the raceway and in one desirable embodiment comprises a transversely reciprocatory cross head carrying two fingers, one or the other of which is arranged to stand always in the path of fasteners on the raceway. The fingers may be made relatively adjustable so that the number of fasteners contained between them and released by the lower finger on the proper movement of the cross head may be varied

in accordance with the number of fasteners it is desired to set.

Still another feature of the invention, relating to the general organization of fastener setting machines, consists in the provision of suitable transmitting mechanisms interposed between a single cam and the let-off device, the reciprocatory member for actuating the fastener-spacing drum and the plate for advancing and retracting the fastener-engaging fingers, such that each of these three devices shall operate in the proper timed relation. As illustrated hereinafter this may be effected by a suitable arrangement of levers and toothed sectors all of which may be actuated by connection at different points with the cam.

In addition to the features of invention above referred to, my invention also contemplates providing certain improved constructions and arrangements of parts hereinafter described and claimed, the advantages of which will be obvious to those skilled in the art.

Referring now to the accompanying drawings in which is illustrated a hook setting machine embodying the various features of my invention in the best form at present known to me:—

Figure 1 is a view in side elevation of the machine. Fig. 2 is a view in front elevation of the machine. Fig. 3 is a plan view, showing a portion of the cover plate broken away. Fig. 4 is a view in perspective of the mechanism for spreading the hook engaging members. Fig. 5 is a side elevation of one of the spindle carrying frames showing other parts of the machine in section. Fig. 6 is a view in perspective of one of the spindle-carrying frames showing the spindle detached therefrom. Figs. 7 and 8 are sectional views of one hook-engaging member shown respectively in retracted and advanced position. Fig. 9 is a view in transverse section of one of the hook-engaging members. Fig. 10 is a sectional view of the mechanism for actuating the feeding brush and the hook separator. Fig. 11 is a plan view of the hook-engaging members in their contracted position. Fig. 12 is a similar view showing the hook-engaging members in their expanded or spaced position. Figs. 13 to 15 are sectional views of the anvil in position respectively for receiving, setting and releasing hooks. Fig. 16 is a sectional plan view of the anvil-carrying head of the machine. Fig. 17 is a detail view showing one of the hook-engaging fingers in engagement with a hook. Figs. 18 and 19 are sectional views of the clutch mechanism. Fig. 20 is a view in perspective of a portion of the clutch mechanism.

Before proceeding to a detailed description of the various parts of the machine, it will be convenient to refer to the principal

operative parts, their general mode of operation and relative arrangement and then to proceed with a detailed description of their operating mechanism and their relative arrangement to the operative devices of the machine.

The machine illustrated in the drawings has a frame 2 which is provided with bearings for the main shaft 4 having on one end the pulley 6 whereby power is transmitted to the machine. Between the pulley and the main shaft is interposed a clutch 7 which is controlled by the operator for starting the machine through suitable treadle connections. The clutch is so constructed and arranged as to automatically stop the machine after one-third of a revolution by the main shaft, during which period the work, which has been presented to the machine, is punched. When the machine is again set in motion the clutch remains in engagement during the remaining two-thirds of the revolution of the main shaft and then automatically stops the machine in its initial position. During this latter part of the cycle the fasteners are inserted in the previously punched holes and clenched in the work.

The shaft 4 has the crank pin 8 mounted between suitable crank disks and from this crank pin a vertical reciprocation is transmitted to the punching table 14 and the hook carrying anvil 16. Between the punching table and the anvil is located a forwardly extending frame 17 which carries a number of vertically stationary spindles 18 having punches 20 on their lower ends and upsetting dies 22 on their upper ends. When the work has been placed upon the punching table 14 and the machine set in operation, the punching table is elevated forcing the work against the punches and thus perforating the work. The punching table is then lowered and the machine automatically stopped allowing the work to be removed, whereupon the work is placed upon the setting table 24 having the previously punched holes threaded over the ends of the die spindles 26. During these operations hooks have been swept from the raceway to the anvil 16 by the feed brush 28 and have been located upon the anvil 16 in exact alinement with the upsetting dies by the spacing fingers 30. With the hooks arranged in these positions, the anvil 16 moves downwardly toward the work and the hooks are inserted and clenched against the upsetting dies. After the setting operation the anvil is raised and swung outwardly, as shown in Fig. 15, disengaging the hooks and leaving the work free to be removed. The machine is again automatically stopped when the anvil 16 is in its elevated position and the punching table 14 in its lowered position, the latter having remained at rest during the setting operation.

Having briefly indicated the general nature and operation of the machine, the various elements and their combinations will now be more particularly described.

The shaft 4 is made in two sections and fast on the adjacent ends of these sections are the crank disks 10 and 12, shown in Fig. 3, connected by a single crank pin 8 to which are connected two oppositely extending connecting rods 31 and 51. The connecting rods each comprise two relatively adjustable sections the inner sections being formed with journal boxes to receive the crank pin 8 and threaded sockets within which are received the threaded ends of the outer slotted sections. The downwardly extending connecting rod 31 has pin and slot connection with the rear end of the lever 32 fulcrumed on the journal pin 33. The journal pin 33 is formed eccentrically on the transverse shaft 34 to which is keyed the worm wheel 35 which meshes with a worm 36 on the end of a short shaft 37 carrying on its forward end the hand wheel 38. It will be seen that the position of the journal pin 33 may be adjusted by turning the hand wheel 38, thus bodily shifting the position of the lever 32 and so adjusting pressure of the piercing table 14 against the punches 20 as will be more particularly described hereinafter.

The piercing or punching table 14 is rigidly attached to the upper end of the plunger 40 mounted for vertical reciprocation in ways formed in the forward part of the frame 2 behind the cover plate 41. The plunger 40 is recessed at two points symmetrically disposed with respect to its axis and the forward end of the lever 32 is forked and provided with rounded ends 39 which engage in said recesses and serve to actuate the plunger when the forward end of the lever 32 is elevated. Owing to the pin and slot connection between the lever 32 and the connecting rod 31 it will be seen that the piercing table 14 is positively actuated only to make the punching stroke. For the purpose of retracting the piercing table after the punching operation there is provided a heavy tension spring 45 which is attached to the under side of the table 14 and swiveled about the upper end of a headed pin adjustably mounted in a lug 46 projecting from the front of the frame. By turning a knurled nut 47 threaded on the lower end of the pin the tension of the spring 45 may be adjusted to the desired amount. Extending across the rear surface of the piercing table is a cutting block 49 of brass or other relatively soft material with which the punches 20 coöperate when the piercing table is elevated.

A detachable edge gage 63 is located at the rear of the piercing table and is made to conform in outline to the average shape of the edge of a quarter of the particular style of

shoe being operated upon. Other edge gages of different outlines may be substituted if it is desired to operate on a style of shoe having a radically different shape of quarter.

In order to bring the edge of the work into continuous contact with the edge gage 63, to take care of slight differences in outline and insure the proper location of the holes to be punched, means are provided for engaging the work located upon the piercing table and drawing it toward the edge gage before the work is moved into contact with the punches. To this end the serrated fingers 65 are arranged to occupy a normal position slightly above the work when the machine is at rest and to engage with the work when the machine is set in operation and the work elevated and thereupon to move rearwardly drawing the work up to the edge gage.

The fingers 63 are forked at their forward ends and each one straddles the end of a punch 20. At the rear ends the fingers are pivotally connected with a transversely extending bar 66 which is actuated forwardly and rearwardly by the bell crank lever 67 through the medium of the slotted link 68 which is pivoted to the lever 32. The pin and slot connection between the link 68 and the lever 32 permits lost motion between the two until the punching table has been elevated enough to carry the work into engagement with the fingers 65 after which the fingers are actuated for rearward movement. The bar 66 is pivotally connected with the lever 67 and is normally maintained in such a position as to hold the fingers 65 elevated by means of a tension spring 69 extending between a lug on the back of the bar 66 and another lug on the lever 67. Each of the fingers is formed of resilient stock and is provided with a cam projection 70 which cooperates with a transversely extending pin 71 tending to move the fingers downwardly for increasing their pressure on the work as they are drawn toward the gage. The pin 71, which constitutes, in effect, a fulcrum over which the fingers 65 are arranged to bend, is eccentrically mounted and extends through one side of the frame 2, where it is provided with a knurled nut (not shown), thus affording means for adjusting the position of the pin and thereby the pressure of the fingers 65 upon the work. During the punching operation the forward ends of the fingers are carried upward as the work table is elevated, bending about the pin 71. After the punching operation the fingers are moved forwardly and finally allowed to disengage the work. In addition to the function of drawing the work up to the edge gage above described, it will be apparent that the fingers also serve as strippers for the punches 20.

Mounted in the frame 17 are a plurality of spindles 18 having formed integral there-

with or otherwise rigidly attached thereto an upper thrust-receiving block 23 and a lower thrust-receiving block 21 slidably engaging the upper and lower surfaces of the frame 17. The punches 20 are adjustably mounted in the lower thrust-receiving block 21, as shown in Fig. 5, and the upsetting dies 22 are adjustably mounted in the upper thrust-receiving blocks 23. The upsetting dies are provided with the usual center spindles 26 for engaging the barrels of the hooks and centering them with respect to the dies. The body portion of each spindle is squared off, as shown in Fig. 6, and engaged by a forked spindle frame 73 each of which is independently pivoted at 74 to the frame 17. The spindles are pressed forwardly by the spring pressed plungers 75 mounted in the spindle frames and are limited in their outward movement by outline plates 76 which are removably mounted in the face plate 77. The outline plates 76, like the edge gage 63, are made to conform in contour to the approximate shape of shoes of the particular style being operated upon. As the difference in the curvature in the line of hooks in shoes of different sizes of the same style is slight, the adjustment of the dies along the contour of the outline plates 76, effected by turning the disk 86, brings the dies into sufficiently close conformity to the various shoe uppers to be operated upon for all practical purposes. The face plate 77 carries the setting table 24 and is removably mounted on the frame 17 by means of the screws 78 and by removing either of these screws the face plate can be swung outwardly upon the other as a hinge, thus affording convenient access to the interior of the face plate for the purpose of inserting outline plates of a different contour or for removing one or more spindle frames in case it is desired to adapt the machine for setting a less number of hooks.

The spindle frames 73 are provided with two rearwardly extending arms for engaging the pivot pins 74 and mounted in the upper arm of each frame is a cam pin 79 which projects downwardly into a cam groove formed in a transversely extending cam drum 81, see Fig. 5. It will be seen that on opening the face plate 77 the spindle frames may be detached and removed by simply moving them toward the front of the machine, each spindle frame being normally held in engagement with its respective pivot by the reaction of the spring pressed plungers 75. The cam drum 81 is mounted upon a shaft 82 which is provided with a knurled nut 83 on the side of the frame 17 whereby the cam drum may be rotated for laterally adjusting the position of the spindles 18. The lateral positions of the spindles are thus controlled by the cam drum 81 while their position from back to front is controlled by

the outline plates 76 against which they are yieldingly maintained. A toothed disk 86 having suitable size indicating graduations on its periphery is also mounted on the shaft 82 and there is provided a spring actuated 5 detent 87 for engaging any one of the notches of the disk 86 and thus positively locking the cam drum in a predetermined position corresponding to a given spread of 10 the spindles. It will be noted that adjustment of the spindles 18 effects a corresponding adjustment of the punches 20 and upsetting dies 22 so that the latter are always 15 in vertical alinement with the punches throughout the whole range of adjustment.

Connected with the lower block 21 of the extreme left hand spindle, shown in Fig. 2, is a transversely extending slide 19 having a T-slot formed therein. A T-headed spindle 20 is adjustably mounted in the slot and has yieldingly mounted on its lower end an end gage 25 against which the tops of two quarters W are to be rested when in position for the punching operation. This gage is, therefore, 25 adjustable with the punches and upsetting dies when these elements are shifted laterally and thus insures a uniform distance between the top of the quarter and the uppermost hole regardless of the adjusted 30 position of the punches. If it is desired to vary this distance a set nut on the spindle may be loosened and the spindle moved to a different position on the slide 19. The gage 25 is yieldingly maintained against the 35 punching table by a spring which encircles the spindle and is provided with a tubular shank which telescopes upon the spindle during the upward movement of the table.

The hook carrier or anvil 16 which coöperates with the upsetting dies 22 is mounted 40 on a reciprocatory head 90 which is guided upon the upper portion of the frame and maintained in engagement therewith by the gibs 92, see Fig. 16, which are secured to the 45 head and slide in corresponding grooves formed in the frame. The head 90 is recessed at two points symmetrically arranged with respect to its axis for the reception of the forked ends 59 of the actuating lever 52 50 and is limited in its upward movement by a stop 91 fast on the frame. The lever 52 is fulcrumed upon a journal pin 53 eccentrically formed on a transverse shaft 54 which is provided at its outer end with 55 a worm wheel 55. The worm wheel 55 meshes with a worm 56 formed on the rear end of the shaft 57 provided with a small hand wheel 58 by which the shaft may be rotated for shifting the journal pin 53 60 and thus adjusting the position of the actuating lever 52, the forward ends 59 of which are rounded and bear against hardened blocks with which the recesses in the head 90 are surfaced. The construction of the ac-

tuating lever 52 and its mounting is substantially similar to the construction described in connection with the lower lever 32 for actuating the punching table. At its rear end the lever 52 has a pin and slot connection with the upwardly extending connecting rod 51 and the end of the lever 52 is normally held in the bottom of the slot in the connecting rod by means of a stiff leaf spring 60 attached to the back of the lever and engaging a pin 61 extending from a 75 projection on the end of connecting rod 51.

The arrangement of the pin and slot connections of the connecting rods 31 and 51 with the actuating levers 32 and 52 is such that on rotation of the crank pin in the direction of the arrow, shown in Fig. 1, the lever 32 is immediately actuated for elevating the piercing table 14 while lost motion occurs between connecting rod 51 and the lever 52 until the crank pin has made one-third of a revolution. During this period the piercing table has been elevated for the punching operation and then lowered under the actuation of the spring 45. From this period lost motion occurs between the connecting rod 31 and the lever 32 for the remaining two thirds of the revolution and during this period the lever 52 is oscillated causing the head 90 to make a reciprocation for inserting the hooks in the work and 95 clenching them in coöperation with the upsetting dies 22.

The anvil 16 upon which the hooks are set conforms in outline with the outline plates 76 and comprises in part a horizontally extending lip which constitutes, in effect, a continuation of the outer rail of a raceway to which hooks are delivered from a magazine in a manner which will be more particularly described hereinafter. Mechanism, 100 also to be hereinafter described is provided for delivering the hooks from the end of the raceway to the center of the anvil 16 as indicated in Fig. 11. The plate 129 mounted in the head 90 in the plane of the horizontal lip 105 serves as a continuation of the inner rail of the raceway.

The anvil is rigidly attached to a transverse member 93 pivotally mounted on the reciprocatory head 90 and having an outwardly projecting abutment against which bears a spring pressed plunger 94 mounted in a bracket on the head 90. This plunger serves to maintain the anvil 16 normally in vertical position, as shown in Fig. 13, and its pressure may be regulated by means of an adjusting screw 95. An adjustable stop 96 extends transversely of the member 93 and by engaging a portion of the head 90 110 serves to regulate the position of the anvil.

After the anvil has been forced to its lowest position, thereby clenching the hooks against the upsetting dies, it is swung out-

wardly from engagement with the hooks and so leaves the work free to be removed from the machine. To this end a throw-out cam 97 is pivoted to the frame of the machine and is normally projected into the path of the member 93 by a small spring pressed plunger. The lower rear edge of the head 90 is beveled off and so disposed as to ride over the back of the cam 97 during its downward movement and force the cam out of the path but on its upward movement the tail 98 of the cam prevents the cam from swinging inwardly and forces the anvil outwardly as shown in Fig. 15.

15 Resilient hook spacing fingers 30 are arranged to move forwardly and engage the hooks pressing them against the anvil 16 and then to move laterally spacing the hooks in exact alinement with the upsetting dies 20 which have previously been spaced by turning the disk 86 in a manner already described. The ends of the fingers 30 are spoon shaped, in order to inclose the head of a hook and have slightly inturned edges as 25 shown in Fig. 17 which are adapted to hook under the edges of the head and insure a positive interlocking engagement between the finger and the hook so as to avoid any possibility of the hook escaping from the 30 finger before it has been properly positioned in alinement with the corresponding upsetting die. Each of the fingers 30 is attached to a bar 112, shown in Figs. 7 to 9, which is connected by the downwardly extending cam 35 roller 118 to the plate 114 which is mounted for sliding movement forwardly and rearwardly and in such movement carries the fingers 30 bodily with it. Each bar 112 is 40 slidingly connected with a channel bar 115 which serve as guides for the bars 112 when the latter are moved longitudinally by the shifting of the plate 114. Each of the guide bars 115 is independently pivoted at its rear end on a pin 116 extending downwardly 45 from a transverse bar 117 mounted on the head 90 and projecting upwardly from each guide bar is a cam roller 118 extending into engagement with a cam groove formed in a second transversely extending cam drum 119 50 rigidly connected with the shaft 120 which is provided with a pinion 121 whereby the shaft and cam drum may be rotated for spreading the guides 115 and thereby the fingers 30 after they have been moved forwardly to engage the hooks.

In order to make the guide bars 115 readily removable their rear ends are forked for engagement with the pivot pins 116 and the guides are provided with rounded channels in their upper surfaces, as shown in Fig. 11, through which channels extend a removable bar 123 mounted below the bar 117 above mentioned. By drawing out the bar 123 the guides 115 are left free for removal 65 by movement toward the front of the ma-

chine. In this way the number of the hook-engaging members may be easily reduced in accordance with the number of hooks it may be desired to set, the remaining hook-engaging members being unaffected by such removal. 70

The plate 114 is moved forwardly and rearwardly by an extension 130 of the lever 131 which is actuated by link 132 pivoted to the bell crank lever 133. One arm of the bell crank lever 133 is in the form of a toothed segment which engages a corresponding segment forming a part of the bell crank lever 134 which in turn is actuated by the cam roller 135 running in a cam groove 80 136 in the cam disk 137. The mechanism just described is so timed as to move the plate 114 and the fingers 30 forwardly when the head 90 and anvil 16 are in their upper position and rearwardly after the head has been lowered for setting the hooks and is being again elevated to its initial position. In order that the plate 114 and its actuating lever may be in operative connection regardless of the vertical position of the anvil, the plate 114 is recessed at two points and slidingly engages the projections 130 above referred to. 85

After the plate 114 has been moved forward and the spoon-shaped ends of the resilient hook spacing fingers have engaged the heads of the hooks, as illustrated in Figs. 8 and 12, the cam drum 119 is rotated an amount determined by the position of the toothed disk 86 as will appear hereinafter. Rotation of the cam drum 119 effects spreading of the guide bars 115 and thereby the fingers 30 and thus moves the hooks into alinement with the previously adjusted upsetting dies. It will be apparent that the outer fingers must be given a rearward motion as they are spread in order that they may move in conformity with the anvil and to this end cam grooves 140, conforming in outline approximately to the contour of the anvil, are provided in the plate 114 and co-operating therewith are the cam rollers 118 mounted in the finger-carrying bars as above described. It will be seen that as the bars 112 are moved laterally with respect to the plate 114 by rotation of the cam drum 119 they are also shifted longitudinally with respect to the guide bars and retracted in accordance with the contour of the anvil by the cam grooves 140. The hook-engaging 100 portions of the fingers 30, however, are elongated somewhat to permit a slight longitudinal relative movement of the hooks without danger of disengagement in order to allow for any variance between the curvature of the anvil and the cam slots 140. 105

The extreme outside guide bar is formed with two channels, the inner one of which carries the hook spreading finger which is to engage the hook to be set nearest the top of 110

the quarter and the outer channel carries a stop 143 which projects across the anvil 14 and serves to limit the movement of the hooks as they are carried on the anvil. The stop 143 moves laterally as the fingers 30 are spread by rotation of the cam drum 119 keeping a constant distance from the outer finger. The stop is provided with a cam roller, similar to the rollers 113 which run in a cam slot substantially similar to the cam slots 140 except that it is formed in the plate 129 instead of the sliding plate 114. This construction maintains the stop in a forward position independently of the plate 114.

The cam drum 119 is rotated for spreading the spacing fingers 30 by means of a toothed sector 145 which meshes with the pinion 121 on the end of the shaft 120. The sector 145 is pivoted to a rearwardly extending portion of the reciprocating head 90 by means of a pin 146 and is oscillated through the pin 147 which projects into a vertical slot in the head 148 formed on the shaft 149 which is slidably mounted within the sleeve 150. The shaft 149 is reciprocated to effect oscillation of the sector 145 by means of the bell crank lever 152 pivoted to the frame of the machine on the pin 153 and actuated by a cam roller 154 running in the cam groove 136 before mentioned. One arm of the bell crank lever 152 is in the form of a toothed sector and meshes with a rack 156 formed on a sleeve 157 which is slidably mounted to the rear end of the shaft 149. The sleeve 150 has a gear 151 formed in one end thereof and on the other end of the sleeve is formed a spiral adapted to engage with a spiral end of the sleeve 157 as the latter is moved forwardly by the bell crank lever 152. The shaft 149 is provided with a nut in its rear end with which the rear end of the sleeve 157 will engage on its rearward stroke and so return the shaft to its initial position regardless of variations in its forward stroke. This arrangement of co-operating spiral sleeves permits a varying amount of lost motion to occur between the sleeve 157 and the head 148. If the sleeve 150 is turned to such an extent that its rear end just engages the forward end of the sleeve 157 it will be apparent that the entire motion of the sleeve 157 will be transmitted to the head 148, through the sleeve 150, but if the sleeve 150 is turned in such a manner that there is a space between its rear end and the forward end of the sleeve 157 it will be clear that the motion of the head 148 is less than the motion of the sleeve 157 by the amount of this space. The sleeve 150 is rotated to vary the throw of the head 148 through a rack comprising the part 163 upon which is formed a rack meshing with a gear 151, and the part 164 upon which is formed a rack meshing with an elongated idle pinion 165. The pin-

ion 165 is arranged to mesh with a rack 166 formed on the lower surface of a horizontally extending bar having a second rack 168 formed upon its upper surface. The rack 168 is arranged to mesh with a second elongated pinion 169 keyed or otherwise rigidly attached to the shaft 82 and actuated by the hand wheel 83 when the latter is turned to effect the adjustment of the punches and upsetting dies in a manner already described.

The mechanism for actuating the cam drums 119 and 81 is so designed and proportioned that when the punches and upsetting dies have been adjusted for the desired spacing the rotation of the cam drum 119 will spread the hook engaging fingers 30 to positions in exact vertical alignment with the upsetting dies 22. One setting of the toothed disk 86, therefore, results in adjusting all the elements of the machine for punching the holes and setting the hooks with any desired spacing.

The hook supplying means comprises a conical magazine 180 having a covered hopper 182 into which hooks may be poured and within the magazine there is mounted for oscillation a segmental blade 184 which is separated from the walls of the magazine by a space just sufficient to receive the head of a hook. The blade 184 is connected with a sleeve 185 frictionally mounted on a central shaft 186 which projects through the rear of the magazine and is provided with a pinion 188 meshing with a toothed sector 189 pivoted to a stationary arm on the frame and oscillated by the connecting link 190 which in turn is actuated by a crank pin 192 which is adjustably mounted in the slot formed in the outer face of the disk 194. The disk 194 is keyed or otherwise rigidly attached to a shaft 196, see Fig. 10, which carries a spiral gear 197 meshing with a large spiral gear 198 on the main shaft 4. It will be seen that rotation of the disk 194 carries the blade 184 into its highest position and allows it to remain practically stationary as it passes the dead point, during which period the hooks which have been carried up on the blade have opportunity to slide from it to the raceway. One rail of the upper end of the raceway 200 extends into the magazine 180 through an aperture in its smaller base while the end of the other, or hook carrying rail is cut off flush with the inner surface of the base. When the blade 184 is in its highest position it constitutes a continuation of this hook carrying rail, thus forming a complete raceway extension within the magazine.

The blade 184 preferably comprises a segment of about 180° and in its oscillations is adapted to cut into the mass of hooks in the magazine and stir them in order to make some hooks assume a proper position to be engaged by the edge of the blade. The

spokes which connect the blades and the sleeve 185 also act to stir the hooks in the magazine as the blade is oscillated back and forth. It may be desirable in the case of 5 some fasteners, to deliver them from the hook-carrying portion of the blade before the latter reaches the highest point in its path, as illustrated in Fig. 2, in order that gravity may act more effectually to maintain 10 the hooks on the blade as they slide toward the raceway, and such an arrangement would make the guard rail within the magazine unnecessary.

A let-off mechanism, best shown in Fig. 3, 15 is located at a point on the raceway below the magazine for feeding the hooks to the delivery end of the raceway as they are required. This mechanism comprises a cross head 220 mounted in guide pins 222 and 20 actuated transversely to and from the raceway by means of spiral teeth 224, formed on the outer end of an arm of the bell crank lever 134 which engages similarly shaped teeth on the lower side of the cross head. 25 Mounted on the upper end of the cross head is a resilient finger 226 which normally interrupts the passage of hooks along the raceway by engaging and pressing one hook against it and has formed therein a recess 30 through which the hooks may pass when the cross head is moved to its outward position. The finger 226 is adjustable longitudinally of the cross head toward and from the finger 228 which extends parallel therewith 35 from the lower end of the cross head. When the cross head is moved toward the right, Fig. 3, the hooks are allowed to pass through the recess in the finger 226 but are arrested by the lower finger 228. On moving the 40 cross head in the opposite direction the hooks contained between the two fingers are released and allowed to continue down the raceway while the upper finger 226 is again moved into its obstructing position. The 45 machine is illustrated in the present drawings as adapted for setting simultaneously eight hooks and the distance between the fingers 226 and 228 in the present case is therefore sufficient to contain eight hooks. 50 If it should be desired to set a different number of hooks the position of the finger 226 is correspondingly adjusted in order that the desired number of hooks may be contained between the two fingers and released at each 55 movement of the cross head toward the left.

When the group of hooks have been released by the let-off mechanism they are allowed to run down the raceway 200, until they encounter a feed brush 28, see Fig. 11. 60 This device comprises an endless belt running on the pulleys 232 and 234 and carrying brushes extending downwardly into the path of the heads of hooks upon the raceway 200. The feed belt is arranged to be 65 set in motion at the time the hooks are re-

leased by the let-off mechanism so that it acts to sweep the hooks along the raceway until they bring up against the stop 230, located at the end of the raceway adjacent the anvil. The stop 230 at its rear end is pivot- 70 ed to the lever 131 which actuates the plate 114 to advance and retract the hook engag- 75 ing fingers 30. The stop, therefore, will be retracted when the plate 114 is moved rear- wardly and the feed brush, which has con- tinued to operate while the group of hooks are thus momentarily delayed by the stop, then sweeps the hooks forwardly to the anvil 16 and carries them to the stop 143 above mentioned. 80

In order to actuate the brush at the proper time the pulley 234 is mounted on the lower end of a shaft 235 carrying on its upper end a pinion 236 which meshes with a gear 237 carried by the shaft 238. A bevel gear 239 is also carried by the shaft 238 and meshes with a bevel gear 240 on the forward end of a shaft 241. The shaft 241 carries on its rear end a small pinion 242 which meshes with an annular gear 243 keyed to the shaft 90 244. The shaft 244 carries one element 246 of a clutch and is normally held in a disengaged position by the spring 247 which encircles the shaft and tends to move it toward the left (Fig. 10). The fast member of the 95 clutch comprises a cone 250 rigid with the spiral gear 197, above referred to. The clutch is intermittently caused to engage by the bell crank lever 252 which is actuated by a cam roller 254 running in a cam groove 100 256 formed in the face of the spiral gear 198. When the clutch is caused to engage, the shaft 241 and the pulley 234 are set in motion and the belt brush 28 acts to sweep the hooks to the anvil as already described. The 105 cam groove 256 is so shaped as to cause the clutch 246, 250 to become engaged during that part of the cycle of the machine in which the punching operation takes place. The feeding mechanism is therefore oper- 110 ated automatically while the setting mechanism remains at rest. The driving pulley 234 for the feeding belt, the clutch 246, 250 through which it is actuated, and the inter- 115 posed, gearing are inclosed in a protecting casing 231 attached to the frame of the machine, as shown in Fig. 1.

It is important in the operation of fastener-setting machines that the machines should always come to rest when the power 120 is disconnected therefrom with the parts in such position that the work may be removed and new work entered therein, and to this end various clutch mechanism may be employed. The clutch mechanism illus- 125 trated in the drawings has been found to be efficient for operating this machine and is the clutch mechanism in connection with which the invention is preferably embodied.

The pulley 6 is keyed to a sleeve 271 130

which runs freely with the pulley and is formed integral or otherwise rigidly attached to a ratchet wheel 272, which of course, also rotates with the pulley 6. The ratchet wheel 272 and the sleeve 271 are journaled on a second sleeve 273 which is keyed to the driving shaft 4 of the machine and which carries a disk 274 on which is formed an arm carrying a pawl 275 which is adapted to engage with the teeth of the ratchet wheel 272 for coupling the driving and driven parts of the clutch together. That is to say, when the pawl is held against the ratchet wheel 272 the ratchet wheel, through the pawl 275, drives the disk 274 and thus the shaft 4.

In order to control the action of the pawl for causing the clutch to engage or disengage, the following mechanism is provided. Rigidly connected with the pivot pin of the pawl 275 is an actuating lever 276 which is received in a recess formed in the periphery of a disk 277 loosely mounted on the driven shaft 4 but connected by a tension spring 278 to the disk 274 which, as noted, is mounted to turn with the driven shaft. The spring 278 tends normally to rotate the disk 277 slightly with respect to the pawl-carrying disk 274 in the direction of the arrow, Fig. 20, and so swing the pawl, through the medium of the lever 276, into engagement with the ratchet wheel. The disk 277 and the pawl-carrying disk 274 thereupon rotate together and the pawl and ratchet remain in engagement until the two disks are given a relative rotation in the opposite direction. It will be apparent that this may be effected by retarding the rotation of the disk 277, thus causing a relative movement of the two disks in the opposite direction to that indicated by the arrow in Fig. 20, which will throw the pawl out of engagement with the ratchet and allow the driven parts to come to rest.

As already pointed out, it is important to stop the machine at definite points in its cycle and in the present machine these points occur at one third and at three thirds of a revolution of the driven shaft. In order to effect automatic disengagement of the clutch at these points, a governing disk 280 is rigidly mounted on the driven shaft 4 and is provided with two teeth located 120° apart in its periphery. A treadle controlled dog 281 is pivotally mounted on the frame 2 of the machine and is normally held against the periphery of the disk 280 by a spring 282 which encircles the treadle rod 183.

As shown in Fig. 18, the machine is at rest after completing one third of a revolution, and the clutch disengaged, the pawl 275 being held out of engagement with the ratchet wheel. When the treadle rod is depressed the dog 281 is disengaged from the

tooth of the governing disk 280 and the spring 278 is allowed to rotate the disk 274 and the disk 280 carried therewith, causing the clutch to engage, as already described. The treadle is then immediately released and the dog 281 returns to a position for engaging the next tooth of the governing disk which is carried into engagement with the dog when the disk has made two thirds of a revolution. When this tooth is encountered the rotation of the driven parts, including the disk 277, is retarded and the pawl moved out of engagement with the ratchet wheel 272. In order to stop the motion of the driven parts immediately when released from the actuation of the driving parts, a brake shoe 279 is mounted on the pawl pivot pin and is arranged to contact with an annular brake rib 284, formed on the inside of the clutch casing. The dog 281 is provided with a tail which stands in the path of the teeth on the governing disk when the treadle is depressed and this serves to positively lift the treadle rod if the operator should neglect to release it immediately after setting the machine in motion. The treadle rod itself is provided with a collar 285 which plays in a small gland in which is provided absorbent material for preventing oil from the clutch from running down the treadle rod.

From the foregoing description the operation of the present machine will be obvious. As indicated in Fig. 2 the quarters W of a shoe may be advantageously superposed and punched at a single operation of the machine. After the punching operation the quarters are removed and separated. The holes in the quarter which has been uppermost in the punching operation will coincide exactly with the positions of the center spindles 26 of the up-setting dies and may be threaded over the spindles with the work in the same position as when removed from the punching table. The other quarter however is turned over to bring its finished surface uppermost and also turned end for end. In this position the two end holes will register exactly with the center spindles of the outside setting dies and the deflection of the curve of the intermediate holes from the curve of the intermediate setting dies will be so slight that each hole may be readily threaded over a corresponding spindle.

Having thus indicated the nature of my invention and having specifically described a machine embodying a preferred form thereof, I claim as new and desire to secure by Letters Patent of the United States:

1. A machine for setting fasteners in sheet material, having, in combination, gang setting devices, power operated fastener supplying mechanism, a clutch for starting and stopping said supplying mechanism, and a

cam for automatically engaging and disengaging said clutch.

2. A machine for setting fasteners in sheet material, comprising fastener-setting mechanism, mechanism for supplying said setting mechanism with fasteners ready for insertion in the work, automatic means for stopping the setting mechanism, a normally stationary actuator for the fastener supplying mechanism, and means for automatically throwing the actuator into action when the setting mechanism is stopped.

3. A machine of the class described, having, in combination, a frame, a punch and upsetting die maintained on opposite sides thereof in vertical alinement, and means located on opposite sides of the frame and movable relatively thereto to coöperate with said punch and die for punching the work and setting a fastener.

4. A machine of the class described, having, in combination, a frame, a spindle mounted therein, a punch carried by one end of said spindle, an upsetting die carried by the other end thereof, and means located respectively beyond the opposite ends of the spindle and coöperating with said punch and die for punching the work and setting a fastener.

5. A machine of the class described having, in combination, a frame having upper and lower horizontal faces, a punch projecting from one face, a die projecting from the other face, a power driven actuator, and separate members for coöperating respectively with the punch and with the die arranged to be moved by said actuator toward the upper and lower faces of the frame for effecting first the punching operation and then the setting operation.

6. A machine of the class described, having, in combination, a stationary frame, a punch and upsetting die mounted thereon and disposed in vertical alinement, means coöperating with the punch for moving the work upwardly for punching the work, and means for inserting a fastener from the upper surface of the work, said latter means coöperating with said die for setting the fastener.

7. A machine of the class described, having, in combination, a stationary frame, an oppositely disposed punch and upsetting die mounted thereon in vertical alinement, means coöperating with the punch for moving the work upwardly for punching the work, fastener supplying means, and a device for receiving fasteners and moving a fastener downwardly to insert it in a previously punched hole in the work.

8. A machine of the class described, having, in combination, a frame, a punch and upsetting die mounted thereon and directed away from each other, a vertically movable

work table coöperating with said punch and a vertically movable anvil for inserting a fastener in the work and setting the fastener in coöperation with said die.

9. A machine of the class described, having, in combination, a frame, an oppositely disposed punch and upsetting die mounted thereon in vertical alinement, a work supporting table, a power operated actuator for positively moving said table for punching the work, separate means for retracting said work table, and means coöperating with said die for setting a fastener in the work.

10. A machine of the class described, having, in combination, a frame, a punch and upsetting die mounted thereon, a work supporting table, a power actuated operator for positively moving said table for punching the work, means for yieldingly retracting said table after the punching operation, and means coöperating with said die for setting a fastener in the work.

11. A hook setting machine having setting devices including a movable hook carrier, a clutch for starting and stopping the movement of said carrier, hook feeding means including a member movable to place a hook on the carrier, and actuating mechanism for said member including a clutch arranged to be automatically thrown into and out of engagement.

12. A hook setting machine having setting devices including a movable hook carrier, a clutch for starting and stopping the movement of the carrier, a raceway, transferring means movable to transfer one hook after another from the raceway to the carrier, and actuating mechanism for the transferring means including a clutch arranged to be automatically disengaged at the conclusion of the transferring operation.

13. A machine of the class described, having, in combination, a frame, a corresponding number of punches and upsetting dies maintained always on opposite sides thereof and always in vertical alinement, means coöperating with said punches for punching the work, and separate means coöperating with said upsetting dies for setting fasteners in the work.

14. A machine of the class described, having, in combination, a frame, a plurality of spindles mounted therein, a punch carried by one end of each spindle, an upsetting die carried by the other end of each spindle, and power operated devices coöoperating with said punches and upsetting dies and respectively movable in opposite directions for punching the work and setting fasteners therein.

15. A machine for setting fasteners in sheet material comprising, a carrier for a gang of fasteners, a raceway having a single delivering opening for supplying all the

fasteners to the carrier, and transferring mechanism constructed and arranged to be set in operation automatically to transfer the fasteners successively from said delivering opening in the raceway to the carrier and to be stopped automatically when the carrier has been so supplied.

16. A machine of the class described, having, in combination, a frame, a corresponding number of punches and upsetting dies mounted thereon and disposed in vertical alinement, means coöperating with the punches for moving the work upwardly for punching the work, and means for inserting a fastener in each hole from the upper surface of the work; said latter means coöperating with said upsetting dies for setting the fasteners.

17. A machine of the class described, having, in combination, a frame, a corresponding number of oppositely disposed punches and upsetting dies mounted thereon in vertical alinement, means coöperating with the punches for moving the work upwardly for punching the work, fastener supplying means, and a device for receiving fasteners and moving them downwardly to insert them in previously punched holes in the work.

18. A machine of the class described, having, in combination, a frame, a corresponding number of oppositely disposed punches and upsetting dies mounted thereon, and maintained always in vertical alinement, a work supporting table, means for positively moving said table for punching the work, separate means for retracting said work table, and means coöperating with said upsetting dies for setting fasteners in the work.

19. A machine of the class described, having, in combination, a frame, a plurality of punches mounted on one side of said frame, a corresponding number of upsetting dies mounted on the opposite side of said frame, and means for simultaneously adjusting said punches and dies, together with means coöperating with said punches and upsetting dies for punching the work and setting fasteners therein.

20. A machine of the class described, having, in combination, a frame, a plurality of punches mounted on one side of the frame and a corresponding number of upsetting dies mounted on another side of said frame, means for simultaneously adjusting said punches and dies, work supporting means relatively movable with respect to said frame for presenting the work to the punches, and means coöperating with said upsetting dies for setting fasteners in the work.

21. A machine of the class described, having, in combination, a frame, a corresponding number of punches and upsetting dies mounted on opposite sides thereof in vertical alinement, means for adjusting said punches

and simultaneously adjusting said upsetting dies, means coöperating with said punches for punching the work, and separate means coöperating with said upsetting dies for setting fasteners in the work.

22. A machine of the class described, having, in combination, a frame, a plurality of spindles mounted therein, a punch carried by one end of each spindle, an upsetting die carried by the other end of each spindle, means for laterally adjusting said spindles, and means coöperating with said punches and upsetting dies for punching the work and setting fasteners therein.

23. A machine of the class described, having, in combination, a supporting member, a corresponding number of punches and upsetting dies mounted thereon, means for simultaneously adjusting said punches and upsetting dies, means for forcing the work against the punches for punching the work, and means operating independently of the punching means for inserting a fastener in each of the previously punched holes and clenching said fasteners in coöperation with said upsetting dies.

24. A machine of the class described, having, in combination, a frame, a corresponding number of punches and upsetting dies mounted thereon and disposed in vertical alinement, means for simultaneously adjusting said punches and upsetting dies, means coöperating with the punches for moving the work upwardly for punching it, and a hook carrier for inserting a hook in each hole from the upper surface of the work, said carrier coöperating with said upsetting dies for setting the hooks.

25. A machine of the class described, having, in combination, a frame, a corresponding number of oppositely disposed punches and upsetting dies mounted thereon in vertical alinement, means for simultaneously adjusting said punches and dies, a work table movable toward and from said punches to present the work to the punches, fastener supplying means and a device for receiving fasteners and moving them downwardly to insert them in previously punched holes in the work.

26. A machine of the class described, having, in combination, a frame, a corresponding number of oppositely disposed punches and upsetting dies mounted thereon and maintained always in vertical alinement, means for simultaneously adjusting said punches and dies laterally, a work supporting table, means for positively moving said table for punching the work, separate means for retracting said work table, and means coöperating with said upsetting dies for setting fasteners in the work.

27. A machine of the class described, having, in combination, a plurality of laterally movable punches, laterally movable upset-

ting dies, a raceway for fasteners and means for arranging a plurality of fasteners in alinement with said upsetting dies, together with means for simultaneously adjusting 5 said punches and upsetting dies.

28. A machine of the class described, having, in combination, a plurality of punches and upsetting dies, means for simultaneously adjusting said punches and dies, a stationary raceway for supplying fasteners and means for arranging a plurality of fasteners 10 in alinement with said upsetting dies.

29. A machine of the class described, having, in combination, a plurality of punches 15 and upsetting dies, means for effecting simultaneous lateral adjustment of said punches and upsetting dies, a raceway for supplying fasteners and means for presenting fasteners to said upsetting dies in any 20 adjusted position thereof.

30. A machine of the class described, having, in combination, a raceway, a carrier constituting a continuation thereof, setting instrumentalities arranged to set a plurality 25 of fasteners simultaneously, positive means acting automatically for spreading the hooks on said carrier in position to be acted on by said instrumentalities in all adjusted position thereof, and means for simultaneously 30 adjusting said instrumentalities.

31. A machine of the class described, having, in combination, a raceway, a carrier constituting a continuation thereof, relatively adjustable setting instrumentalities arranged to set a plurality of hooks simultaneously, and spacing means having members for engaging a number of the hooks to be set and moving them automatically to the setting instrumentalities in all adjusted positions thereof, together with means for simultaneously adjusting said instrumentalities. 40

32. A machine of the class described, having, in combination, a raceway, a carrier constituting a continuation thereof, setting 45 instrumentalities arranged to set a plurality of hooks simultaneously, means for effecting simultaneous adjustment of said instrumentalities, and spacing means having members for engaging a number of the hooks to be set and moving them to the setting instrumentalities, said spacing means being constructed to spread automatically said hooks in conformity to the spacing of the setting instrumentalities. 50

33. A machine of the class described, having, in combination, a plurality of setting dies, a carrier for fasteners adapted to support the same in line, an automatically acting device having fingers movable so as to engage a number of fasteners simultaneously and transfer them different distances into correct positions relative to the setting dies, and means for moving the setting dies laterally to adjust their spacing. 55

34. A machine of the class described, hav-

ing, in combination, a plurality of setting dies, a carrier for hooks adapted to support them in line, a device having a plurality of hook-engaging fingers, means for moving said device to engage a number of hooks 70 with said fingers, means for automatically shifting said fingers so as to transfer the hooks to positions on the carrier to be acted on by the setting dies, and means for adjusting the spacing of said setting dies. 75

35. A lacing hook setting machine, having a gang of relatively adjustable upsetting dies, an anvil movable toward and from said upsetting dies and having a continuous hook supporting lip adapted to hold hooks 80 in any position and to carry them toward the upsetting dies to be clenched thereby, a device arranged to engage hooks upon said supporting lip and automatically space them correspondingly to the adjusted positions of the upsetting dies, and means for simultaneously adjusting the upsetting dies. 85

36. A machine of the class described, having, in combination, a plurality of upsetting dies, means for moving the dies laterally for 90 the adjustment thereof, means for carrying a number of hooks simultaneously to said upsetting dies, feeding means for placing hooks on said carrying means, and movable spacing fingers for moving the hooks while 95 upon the carrying means in conformity with the spacing of the upsetting dies.

37. A machine of the class described, having, in combination, a plurality of adjustable upsetting dies, means for carrying simultaneously a number of hooks to said upsetting dies, and resilient fingers constructed to engage and cover the heads of the hooks on said carrying means, spreading them in conformity with the spacing of said upsetting dies and supporting them during 100 the setting operation. 105

38. A machine for setting lacing hooks and the like, having in combination, a gang of adjustable upsetting dies, a reciprocatory 110 carrier for a gang of hooks, a controlling device for spacing the dies of the gang, and automatically acting mechanism for causing hooks delivered to the carrier to be spaced in accordance with the spacing of the dies. 115

39. A machine of the class described, having, in combination, a plurality of punches and upsetting dies, a reciprocatory work table for presenting work to said punches, a reciprocatory carrier for presenting fasteners to said upsetting dies, actuating levers for respectively actuating said work table and carrier, and means for adjusting said actuating levers to regulate the pressure on the punches and on the upsetting 120 dies respectively. 125

40. A machine of the class described having, in combination, adjustable upsetting dies, a co-operating hook carrier, means for delivering a series of hooks to the carrier 130

- in a predetermined spacing, a manually operated device for adjusting the spacing of the upsetting dies, and automatically acting means, controlled in its operation by the setting of said adjusting device, for moving the hooks when the machine is started from their initial position into alinement with the previously adjusted upsetting dies. 7c
41. A machine of the class described having, in combination, a series of upsetting dies relatively movable in a lateral direction to vary their spacing, a coöperating hook carrier, means for delivering a series of hooks to the carrier in a close spacing, an adjusting device operatively connected with the upsetting dies, and automatically acting means, controlled in its operation by the position of said adjusting device, for spreading the hooks apart in the carrier when the machine is started from their initial position into alinement with the previously adjusted upsetting dies. 75
42. A machine of the class described having, in combination, a plurality of relatively adjustable upsetting dies, means for carrying a number of fasteners to the upsetting dies to clench them, a raceway, and spreading means acting automatically, for moving the fasteners into alinement with the dies whatever may be their adjusted positions. 80
43. A machine of the class described having, in combination, a supporting frame having a substantially plane horizontal surface, a spindle adjustably mounted in the frame and carrying a setting die at its end projecting normally above said surface so that it may be inserted in the work, a thrust-receiving block secured to the spindle and arranged to slide upon the surface of the frame, and adjusting mechanism operatively connected to the spindle below the surface of the frame. 85
44. A machine of the class described having, in combination, a supporting frame having a plane surface, a series of die-carrying spindles mounted within the frame and arranged for relative adjustment, setting dies carried by said spindles and disposed with their ends above the frame so that they may be inserted in the work, a thrust-receiving block secured to each spindle and arranged to slide upon the surface of the frame, and adjusting mechanism acting upon the spindles at a distance from the thrust-receiving blocks. 90
45. A machine of the class described having, in combination, a frame having opposite parallel surfaces, a series of carrying spindles adjustably mounted in the frame, each spindle having a block secured near both of its ends and arranged to slide upon the parallel surfaces of the frame, and adjusting mechanism operating upon the spindles between the blocks. 95
46. A machine of the class described hav- 100
- ing, in combination, a plurality of upsetting dies, adjusting mechanism for varying the spacing of the dies, a reciprocatory carrier for fasteners, and means for engaging fasteners on the carrier and locating them relatively to the dies whatever may be the adjusted position of the dies, said means being automatically returned to initial position after each setting operation. 105
47. A machine of the class described, having, in combination, a stationary frame, a reciprocatory head carrying an anvil, fastener spreading devices mounted for movement with the head, an actuating cam mounted in the stationary frame, and connections between the cam and the spreading devices operative in all positions of the head. 110
48. A machine of the class described having, in combination, a stationary frame, a vertically reciprocatory head carrying an anvil, fastener spreading devices mounted in the head, a substantially vertical actuating lever connected with the spreading devices in all positions of the head, and a cam on the frame for swinging the lever. 115
49. A machine of the class described, having, in combination, a plurality of punches and upsetting dies, mechanism for laterally adjusting said punches and upsetting dies, a raceway for supplying fasteners, mechanism for presenting fasteners to said upsetting dies in any adjusted position thereof, and a single device for controlling the operation of said adjusting mechanism and said fastener presenting mechanism. 120
50. A machine of the class described, having, in combination, a plurality of upsetting dies, mechanism for laterally adjusting said dies, a raceway for supplying fasteners, mechanism for presenting fasteners to said upsetting dies in any adjusted position thereof, and a single device for controlling both said mechanisms. 125
51. A machine of the class described, having, in combination, a plurality of upsetting dies, mechanism for laterally adjusting said dies, a hook carrier, hook delivering means, mechanism for locating hooks on said carrier in accordance with the position of said dies, and a single device for actuating the die adjusting mechanism and for controlling the operation of the hook-locating mechanism. 130
52. A machine of the class described, having, in combination, a plurality of upsetting dies, adjusting mechanism therefor, a carrier for fasteners, a raceway for supplying fasteners to the carrier, mechanism for locating fasteners on said carrier in alinement with said dies after the fasteners have been delivered to the carrier, and a single device for actuating said adjusting mechanism and for controlling the operation of the fastener-locating mechanism. 135
53. A machine of the class described, having, in combination, a plurality of upsetting 140

- 5 dies, adjusting mechanism therefor, a carrier for fasteners, fastener supplying means, means for engaging fasteners on said carrier after they leave the supplying means and locating them relative to said dies, and a single device for actuating said adjusting mechanism and for controlling the operation of the fastener-engaging and locating means.
- 10 54. A machine of the class described, having, in combination, a plurality of upsetting dies, adjusting mechanism therefor, a carrier for fasteners, fingers for engaging said fasteners on said carrier, means for moving said fingers relatively to the carrier to locate the fasteners relative to said dies, and a single device for actuating said die-adjusting mechanism and for controlling the operation of the finger-moving means.
- 15 55. A machine of the class described, having, in combination, a plurality of upsetting dies, adjusting mechanism therefor, a carrier for hooks, hook-engaging members, means for moving said members in one direction for engaging hooks on said carrier, means for moving said members in a different direction for locating the hooks relative to said dies, and a device for controlling the operation of the latter means, said device also serving to actuate the die-adjusting mechanism.
- 20 56. A machine of the class described, having, in combination, a plurality of upsetting dies, die-adjusting mechanism; a manually operated device for actuating said mechanism, and means constructed and arranged to operate after the manually operated device has been set for presenting fasteners to said dies in any adjusted position thereof.
- 25 57. A machine of the class described, having, in combination, a plurality of upsetting dies, die-adjusting mechanism, a raceway, means independent of said raceway for presenting fasteners to said dies, and a device for actuating said die-adjusting mechanism.
- 30 58. A machine of the class described, having, in combination, a plurality of setting instrumentalities, adjusting mechanism therefor, a carrier for fasteners, fastener-engaging members, guiding devices for each member, means for moving said members for engaging fasteners on said carrier, and means for moving said guiding devices for locating the fasteners relative to said setting instrumentalities.
- 35 59. A machine of the class described, having, in combination, a plurality of setting instrumentalities, adjusting mechanism therefor, a carrier for fasteners, fastener-engaging members, means for moving said members to engage fasteners on said carrier, separate mechanism for spreading said members, and a single device for actuating said adjusting mechanism and controlling said spreading mechanism.
60. Hook spreading mechanism for a hook setting machine, comprising pivoted guide members, hook-engaging members slidably mounted therein, and means for spreading said guide members. 70
61. Hook spreading mechanism for a hook setting machine, comprising pivoted guide members, hook-engaging members slidably mounted therein, means for moving said members forwardly for engaging hooks, and means for spreading said guide members. 75
62. A machine of the class described, having, in combination, a carrier for fasteners, fastener-engaging members, pivoted guide members therefor, means for swinging said guide members varying distances upon their pivots, and means for causing a relative longitudinal shifting of said fastener-engaging and guiding members. 80
63. A machine of the class described, having, in combination, a carrier for fasteners, a plurality of pivoted guide members, slideable fastener-engaging members mounted therein, means for causing a relative longitudinal shifting of said fastener-engaging and guide members, and means for causing a relative angular movement of said guide-members. 85
64. A machine of the class described, having, in combination, a carrier for fasteners, fastener setting devices, a plurality of guide-members, slideable fastener-engaging members mounted therein, a movable plate connected with said fastener-engaging members, means for advancing said plate to shift said fastener-engaging members longitudinally with respect to said guide members for engaging fasteners on said carrier, and means for spreading said guide-members and fastener-engaging members for moving the fasteners laterally. 95
65. A machine of the class described, having, in combination, a carrier, setting dies co-operating therewith, a plurality of pivoted guide-members, hook-engaging fingers mounted therein, a movable plate connected with said fingers, means for advancing said plate to cause the fingers to engage hooks on said carrier, and means for spreading said guide-members and fingers for moving the hooks laterally. 100
66. A machine of the class described, having, in combination, fastener setting devices, a carrier co-operating therewith, a plurality of pivoted guide-members, fastener-engaging members slidably mounted therein, and means for simultaneously projecting said fastener-engaging members from said guide members for engaging fasteners on said carrier. 110
67. A machine of the class described, having, in combination, fastener setting devices, a carrier, a plurality of pivoted guide-members, fastener-engaging members slidably mounted therein, means for simultaneously 115
- 120
- 125
- 130

- projecting said fastener-engaging members from said guide-members for engaging fasteners on said carrier, and means for spreading the guide-members and fastener-engaging members laterally.
68. A machine of the class described, having, in combination, fastener setting devices, a curved carrier, a plurality of movable fastener-engaging members, means for advancing said members to engage fasteners on said carrier, and means for spreading said members laterally in conformity to the curve of said carrier.
69. A machine for setting lacing hooks and the like, having in combination, a gang of adjustable upsetting dies, a carrier for a gang of hooks movable toward and from said dies, a controlling device for manually spacing the dies of said gang, and automatically acting mechanism having operative connection with the carrier in all positions thereof and acting to cause hooks in the carrier to be spaced in accordance with the spacing of the dies.
70. A machine of the class described, having, in combination, setting instrumentalities, a curved carrier coöperating therewith, a plurality of movable fastener-engaging members having ends shaped to engage fasteners on said carrier, means for advancing said members for engaging such fasteners, and means for moving said members in such a manner that their ends shall follow the curve of said carrier.
71. A machine of the class described, having, in combination, setting instrumentalities, a curved carrier coöperating therewith, a plurality of movable fastener-engaging members, means for advancing said members for engaging fasteners on said carrier, and means for imparting a combined lateral and longitudinal movement to said members for spreading fasteners upon the curved carrier.
72. A machine of the class described, having, in combination, a raceway, fastener-setting instrumentalities, a carrier for fasteners constituting in effect a continuation of said raceway, fastener-engaging members for engaging fasteners on said carrier and spreading them thereon, and a stop for said fasteners movable with one of said members.
73. A machine of the class described, having, in combination, setting devices, a curved carrier, a plurality of movable fastener-engaging members adapted to engage fasteners on said carrier, means for spreading said members, and separate means for shifting them longitudinally in conformity to the curve of said carrier.
74. A machine of the class described, having, in combination, setting devices, a carrier coöperating therewith and shaped to set a line of fasteners on a curve, fastener-engaging members, a plate for moving said members into fastener-engaging position, a cam for spreading said members, and separate means for shifting said members longitudinally simultaneously with the spreading operation in conformity to the curve on which the fasteners are to be set.
75. A machine of the class described, having in combination, setting devices, a carrier coöperating therewith and shaped to set a line of hooks on a curve, fastener-engaging members, spreading mechanism therefor, and a plate having cam slots shaped to correspond with the curve of said carrier and connected with said members in such a way as to cause a longitudinal shifting thereof in conformity with said curve as said members are spread.
76. A machine of the class described, having, in combination, setting devices, a carrier coöperating therewith and shaped to set a line of hooks on a curve, fastener-engaging members, a cam for spreading said members, and separate cams for guiding said members in conformity to the curve.
77. A machine of the class described, having, in combination, hook setting instrumentalities, a carrier for hooks, movable hook-engaging members constructed and arranged, on forward movement thereof, to engage separate hooks on said carrier without changing the relative positions thereof, and means for subsequently moving said hook-engaging members laterally to space the hooks.
78. A machine of the class described, having, in combination, setting instrumentalities, a carrier for fasteners, movable fastener-engaging members constructed and arranged, on forward movement thereof, to engage the heads of fasteners on said carrier without changing the relative positions of the fasteners, and means for subsequently moving said members laterally to space the fasteners.
79. A machine of the class described, having, in combination, hook-setting instrumentalities, a carrier adapted to receive hooks with their barrels extending downwardly, movable hook-engaging members constructed and arranged to engage the heads of hooks upon the carrier without changing the position of the hooks, and means for subsequently moving said members laterally to space the hooks on said carrier.
80. A machine of the class described, having, in combination, fastener-setting instrumentalities, and means for presenting fasteners thereto comprising a carrier, members for engaging fasteners on said carrier, mechanism for spreading said members to space the fasteners, and an actuating device therefor having a variable action.
81. A machine of the class described, having, in combination, fastener-setting instrumentalities, and means for presenting fas-

- teners thereto comprising, a carrier, members for engaging fasteners on said carrier, mechanism for spreading said members, a power-operated actuating device therefor, 5 and means under the control of the operator for varying the action of the actuating device.
82. A machine of the class described, having, in combination, fastener-setting instrumentalities, and means for presenting fasteners thereto comprising, a carrier, members for engaging fasteners on said carrier, mechanism for spreading said members, a reciprocatory rod for actuating said spreading mechanism, and means for varying the length of its reciprocations to regulate the spreading of the fastener-engaging members.
83. A machine of the class described, having, in combination, adjustable setting dies, mechanism for adjusting said dies, and means for presenting fasteners to said dies comprising, a carrier, members for engaging fasteners on said carrier, mechanism for 20 spreading said members to space said fasteners, an actuating device for said spreading mechanism, and means for regulating the action of said actuating device and for simultaneously actuating the adjusting mechanism for said dies.
84. A hook setting machine, having, in combination, hook-spreading fingers, a cam for spreading said fingers, gearing for actuating said cam, a reciprocatory rod for 35 actuating said gearing, a device having a uniform reciprocation for actuating said rod, and means for varying the lost motion between said device and said rod.
85. A hook setting machine, having, in combination, hook-spreading fingers, a reciprocatory rod, mechanism interposed between said fingers and rod whereby the reciprocation of the rod effects spreading of the fingers, a device having a uniform reciprocation for actuating said rod, and means for regulating the motion imparted by said actuating device to said rod.
86. A machine of the class described, having, in combination, setting dies, mechanism 50 for adjusting said dies, fastener-spreading fingers, a reciprocatory rod, mechanism interposed between said fingers and rod whereby the reciprocation of the rod effects spreading of the fingers, a device having a uniform reciprocation for actuating said rod, and means for regulating the motion imparted by said actuating device to said rod in accordance with the position of said die-adjusting mechanism.
87. A machine of the class described, having, in combination, setting dies, mechanism for adjusting said dies, fastener-spreading members, an actuating device therefor having a uniform motion, and interposed mechanism for regulating the motion transmitted 55 from said actuating device to said fastener-spreading members in accordance with the position of the die-adjusting mechanism.
88. A machine of the class described, having, in combination, setting instrumentalities, a reciprocatory carrier, and means for spreading fasteners on said carrier, said later means being mounted for movement with said carrier.
89. A machine of the class described, having, in combination setting instrumentalities, a reciprocatory head, an anvil for fasteners mounted thereon, and members for engaging and spreading fasteners on the anvil, said members being mounted on said reciprocatory head for movement therewith.
90. A machine of the class described, having, in combination, setting instrumentalities, a coöperating carrier for receiving fasteners, and means for moving said fasteners constructed and arranged to press them against said carrier and spread them by lateral movement.
91. A machine of the class described, having, in combination, setting instrumentalities, a coöperating carrier having a continuous fastener-supporting portion, devices for engaging fasteners independently and pressing them against said portion, and means for moving said fastener-engaging devices to spread the fasteners.
92. A machine of the class described, having, in combination, setting instrumentalities, a coöperating carrier having a continuous fastener-supporting portion, resilient fingers for engaging fasteners and pressing them yieldingly against said portion, and means for spreading said fingers.
93. A machine for setting lacing hooks, having means for presenting lacing hooks to hook setting instrumentalities, including a movable hook-engaging member constructed and arranged to inclose the head of a lacing hook and hook under the edges thereof.
94. A machine of the class described, having means for presenting fasteners to hook setting instrumentalities, including a movable fastener-engaging member having inwardly turned edges adapted to hook under the edges of a portion of the fastener.
95. A machine of the class described, having, in combination, setting instrumentalities, a carrier for hooks, and spreading members, each constructed and arranged for interlocking engagement with one end of a hook on said carrier.
96. A machine of the class described, having, in combination, relatively adjustable setting instrumentalities, a carrier for hooks, and means for presenting hooks to said instrumentalities, including independent members constructed and arranged to engage positively hooks on said carrier and spread them in accordance with any adjusted position of the setting instrumentalities.

97. A machine of the class described, having, in combination, a frame, setting instrumentalities removably mounted therein, and fastener-presenting means including a plurality of removably mounted members for engaging and spreading fasteners and means for simultaneously releasing said members for the removal of one or more thereof. 5
98. A machine of the class described, having, in combination, a frame, setting instrumentalities removably mounted therein and fastener presenting means including a plurality of forked fastener-engaging members pivoted for lateral movement, each of said members being provided with a recess, and a single retaining member for engaging the recesses in a number of the fastener-engaging members. 10
99. A machine for setting simultaneously a plurality of fasteners, having, in combination, a frame, a plurality of spindles mounted therein, each carrying a punch and a setting instrumentality, and fastener-spreading fingers mounted in said frame and so arranged as to permit independent removal. 20
100. A machine for setting simultaneously a plurality of fasteners, having, in combination, a frame, a plurality of forked spindle-frames, pivots therefor, punches and setting dies mounted on said spindle-frames, and means for retaining said spindle-frames in engagement with their pivots. 30
101. A machine for setting lacing hooks and the like, having in combination, a gang of laterally adjustable but vertically stationary setting dies, a hook carrier movable vertically toward and from said gang, hook retaining devices movable with the carrier, and automatically acting mechanism for spacing the hooks having operative connection with the hook retaining devices in all positions of the carrier. 35
102. A machine for setting simultaneously a plurality of fasteners, having in combination, a frame, a plurality of spindles movably mounted therein, setting instrumentalities carried thereby, an outline plate, and means for holding said spindles against the contour thereof. 45
103. A machine for setting simultaneously a plurality of fasteners, having in combination, a frame, a plurality of setting devices mounted thereon, an outline plate, and means for maintaining said setting devices arranged in accordance with the contour of the outline plate. 50
104. A machine for setting simultaneously a plurality of fasteners, having in combination, a frame, a plurality of movable setting devices, means for shifting them laterally, and yielding means for causing them to move forwardly in accordance with a predetermined curve. 60
105. A machine for setting simultaneously a plurality of fasteners, having in combination, a plurality of setting devices, frames for said devices, pivots for the frames, means for shifting said frames about their pivots, and means for moving said setting devices toward or from said pivots in accordance with a predetermined curve. 70
106. A machine for setting simultaneously a plurality of fasteners, having in combination, a plurality of setting devices, pivoted frames for said devices, and means for moving said devices longitudinally of said frames in accordance with a predetermined curve simultaneously with the pivotal movement of the frames. 75
107. A machine for setting simultaneously a plurality of fasteners, having in combination, a frame, a plurality of setting devices, a mounting for each of said devices permitting independent lateral and longitudinal movement thereof relative to said frame, and a member having a predetermined curve for controlling the longitudinal position of each setting device in accordance with its lateral position. 80
108. A machine for setting simultaneously a plurality of fasteners, having in combination, a plurality of setting devices mounted for lateral movement and movement at right angles to their lateral movement, and a replaceable device for controlling the latter movement of all of said setting devices. 90
109. A machine of the class described, having, in combination, a plurality of setting devices mounted for lateral adjustment, means for presenting fasteners thereto comprising a fastener-carrier, means for positioning fasteners on said carrier, and a rotatable drum for actuating said means, together with mechanism for rotating said drum an amount determined by the position of said previously adjusted setting devices. 100
110. A machine of the class described, having, in combination, a plurality of setting devices mounted for lateral adjustment, adjusting mechanism therefor and fastener-positioning means, automatically acting at a different time from the adjusting mechanism for the setting devices, to position laterally the fasteners in a correct relation to said setting devices. 110
111. A machine of the class described, having, in combination, a plurality of relatively movable setting devices, adjusting mechanism therefor, and automatically acting means for laterally positioning fasteners in accordance with the position of the previously adjusted setting devices. 120
112. A machine of the class described, having, in combination, a plurality of movable setting devices, actuating means for the setting devices, adjusting mechanism therefor, fastener-positioning means, and a device for actuating said fastener-positioning means to position the fasteners in accordance with the position of the previously adjusted setting devices. 125
- 130

anee with the position of the previously adjusted setting devices.

113. A machine of the class described, having, in combination, a plurality of movable setting devices, adjusting mechanism therefor, fastener-positioning means, a device for actuating said fastener-positioning means, and transmitting mechanism, adjustable simultaneously with said setting devices, for regulating the movement transmitted from said actuating device to said fastener-positioning means.

114. A machine of the class described, having, in combination, a plurality of adjustably mounted punches and setting devices, work-presenting means and a gage arranged for continuous engagement with said work presenting means and for adjustment simultaneously with said punches and setting devices.

115. A machine of the class described having, in combination, a hook carrier, hook spreading members, rotatable cams for controlling their movement, and means for automatically rotating the cams forwardly and backwardly between successive setting operations.

116. A machine of the class described having, in combination, a reciprocatory hook carrier, hook spreading members mounted for movement with the carrier, and rotatable cams arranged to turn automatically in one direction to spread the spreading members and then in the other direction to contract the members between successive setting operations.

117. A machine of the class described having, in combination, a stationary frame, a reciprocatory hook carrier, hook spreading members mounted in the carrier, and separate devices in the frame for advancing the spreading members and for spreading them arranged to have an operative connection with the members in all positions of the carrier.

118. A machine of the class described, having, in combination, setting devices, work supporting means, and means for presenting fasteners to said setting devices including a carrier for fasteners, and a feeding belt for moving fasteners to said carrier.

119. A machine of the class described, having, in combination, setting devices, work supporting means; a raceway, and means for presenting fasteners to said setting devices, including a carrier for fasteners, and a feeding belt for moving fasteners along said raceway toward said carrier.

120. A machine of the class described, having, in combination, setting devices, a carrier for fasteners, and means for presenting fasteners to said setting devices, including a feeding belt constructed and arranged to en-

gage fasteners on said carrier, and move them to a predetermined position thereon.

121. A machine of the class described, having, in combination, setting devices, a carrier for fasteners, a raceway leading thereto, and a feeding belt for transferring fasteners from said raceway to said carrier.

122. A machine of the class described, having, in combination, hook setting devices, a carrier movable toward and from said devices for inserting and clenching hooks in co-operation therewith, a raceway leading to said carrier when the latter is in a position remote from the setting devices, and a belt-carried feed brush actuated when the carrier is in said remote position for feeding hooks thereto.

123. A machine of the class described, having, in combination, setting devices, a raceway, a carrier for fasteners movable from one to the other, and a belt-carried feed brush actuated when the carrier is in position adjacent to the raceway for feeding fasteners from the raceway to the carrier.

124. A machine of the class described, having, in combination, setting devices, a belt-carried feed brush, and a reciprocatory carrier for fasteners movable into and out of operative relation with said feed brush.

125. A machine of the class described, having, in combination, setting devices, a carrier for fasteners, a stop on said carrier, a belt-carried brush for moving fasteners toward said stop, and means for subsequently engaging said fasteners and moving them into alinement with the setting devices.

126. A machine of the class described, having, in combination, setting devices, a carrier for fasteners having a stop, a raceway, a belt-carried brush for transferring fasteners from said raceway to the stop on the carrier, and means for subsequently engaging said fasteners and moving them into alinement with the setting devices.

127. A machine of the class described, having, in combination, adjustable setting devices, a carrier for fasteners, a stop on said carrier, a raceway, a removable stop on said raceway, and a belt-carried brush for moving fasteners to the stop on the raceway and acting on the retraction of said stop to transfer said fasteners to the stop on the carrier.

128. A machine of the class described, having, in combination, setting devices, a carrier for fasteners, a raceway, means for supplying a predetermined number of fasteners to the delivering end of the raceway, and a belt-carried feed brush for transferring said fasteners from the raceway to the carrier.

129. A machine of the class described, having, in combination, setting devices, a raceway for supplying fasteners thereto, and a cooperating let-off mechanism having provision for adjustment whereby the number

of fasteners supplied to the setting devices may be varied.

130. A machine of the class described, having in combination, setting devices, a race-way and let-off mechanism coöperating therewith, comprising a plurality of fingers, and means for moving said fingers alternately into and out of fastener engaging position, said fingers having provision for relative adjustment.

131. A machine of the class described, having in combination, setting devices, a race-way and let-off mechanism coöperating therewith comprising a reciprocatory member, and fingers mounted thereon for movement into and out of position for engaging fasteners in the raceway, one of said fingers being adjustable relative to the other for varying the capacity of the let-off mechanism.

132. A machine for setting simultaneously a number of hooks, having provision for varying the number of hooks set thereby, and having in combination, a raceway and let-off mechanism with provision for adjustment whereby the capacity thereof may be regulated in accordance with the number of hooks to be set.

133. A machine of the class described, having in combination, setting devices, a race-way, a bar movable to and from said race-way, and fingers carried thereby, one of which is provided with a recess intermediate of its length for the passage of a hook upon said raceway.

134. A machine of the class described, having in combination, setting devices, a raceway and a coöperating let-off mechanism including a member constructed and arranged to interrupt the passage of fasteners along the raceway by engaging a fastener and pressing it against the raceway.

135. A machine for setting simultaneously a number of hooks, having provision for varying the number of hooks set thereby, and having in combination, setting devices, a raceway, coöperating let-off mechanism having a variable capacity, and mechanism for presenting the hooks released by the let-off mechanism to the setting devices.

136. A machine of the class described, having in combination, setting devices, means for presenting fasteners to said devices, said means being adapted to handle a variable number of fasteners, a raceway, and coöperating let-off mechanism, the capacity whereof may be varied in accordance with the fastener presenting means.

137. A machine of the class described, having in combination, up-setting dies, a coöperating anvil, fastener-spacing fingers, a raceway, and let-off mechanism associated therewith, the capacity thereof being adjustable to correspond to the number of fastener spacing fingers.

138. A machine of the class described, having in combination, setting devices, punches and fastener spacing members, and mechanism for operating a variable number of each of the above-mentioned elements, together with means for supplying a corresponding number of fasteners to the setting devices.

139. A machine of the class described, having in combination, a frame, a punch mounted on one side thereof, an upsetting die mounted on the other side thereof and directed away from the punch, means coöperating with said punch for punching the work, and a reciprocatory anvil coöperating with said setting die and being constructed and arranged to release a clenched hook by swinging outwardly after the setting operation.

140. A machine of the class described, having in combination, a frame, a plurality of punches mounted on one side thereof, a corresponding number of upsetting dies mounted on the opposite side thereof, means for simultaneously adjusting said punches and dies, means coöperating with said punches for punching the work, and a reciprocatory anvil coöperating with said setting dies and being constructed and arranged to release a clenched fastener by swinging outwardly after the setting operation.

141. A machine of the class described, having in combination, a frame, a plurality of punches and setting dies mounted thereon in a curve, a reciprocatory anvil having a contour curved in accordance with the curve upon which the setting dies are located, and means for swinging said anvil out of engagement with the clenched hooks.

142. A machine of the class described having, in combination, punching devices, setting devices, a common actuator for operating first one and then the other set of devices, and fastener spreading mechanism arranged to position a fastener in alignment with each setting device during the punching operation.

143. A machine of the class described, having in combination, a frame, a plurality of setting devices mounted thereon, means for adjusting said devices upon a predetermined curve, a reciprocatory anvil having a contour corresponding to said curve, and means for moving said anvil in a direction different from that of its reciprocations for disengaging clenched fasteners.

144. A machine of the class described, having in combination, a frame, a plurality of setting devices mounted thereon, guiding means restricting adjusting movement of said devices to a predetermined curve, a coöperating anvil having the contour of its hook retaining portions corresponding to said curve, means for moving said anvil to-

ward said setting devices for setting fasteners in the work, and means for moving said anvil transversely for disengaging clenched fasteners.

5 145. A machine of the class described, having, in combination, a gang of upsetting dies, a reciprocatory hook carrier, transferring mechanism for moving hooks one after another to the carrier, an actuator for 10 the transferring mechanism, and automatic means for connecting and disconnecting said actuator and transferring mechanism.

15 146. A machine of the class described having, in combination, a gang of upsetting dies, a hook carrier movable relatively thereto, hook transferring mechanism, and an actuator therefor arranged to be automatically rendered operative and then inoperative during the cycle of the machine.

20 147. A machine of the class described, having in combination, setting devices, a raceway for supplying fasteners, let-off mechanism associated therewith, a stop for fasteners released by said let-off mechanism, 25 and a common actuating device for said stop and let-off mechanism.

148. A machine of the class described, having in combination, setting devices, an anvil, a raceway for supplying fasteners thereto, means for engaging fasteners on 30 said anvil during the setting operation, let-off mechanism associated with said raceway, and a common actuating device for said let-off mechanism and said fastener-engaging means.

149. A machine of the class described, having in combination, setting devices, an anvil, a raceway for supplying fasteners thereto, a stop on said raceway adjacent said 40 anvil, let-off mechanism associated with said raceway, fastener-engaging means associated with said anvil, and a common actuating device for said stop, let-off mechanism and fastener-engaging means.

45 150. A machine of the class described, having in combination, setting devices, an anvil, a raceway for supplying fasteners thereto, a stop on said raceway adjacent said anvil, fastener-engaging means associated with said anvil, and a common actuating device for said stop and said fastener-engaging means.

151. A machine of the class described having, in combination, a frame having adjustable dies mounted therein, punches arranged in alinement with the dies, a table for moving the work toward and from the punches, and automatic hook spreading means arranged to position hooks in alinement with the previously adjusted dies during the movement of the work table.

152. A machine of the class described having, in combination, a frame having punches and dies mounted therein, adjusting means for said punches and dies, a hook

carrier movable toward the punches, means for delivering hooks to the carrier, means for forcing the work against the punches, and positioning means arranged to act on the hooks after they have been delivered to 70 the carrier and during the punching operation to move the hooks into alinement with the previously adjusted dies.

153. A machine of the class described having, in combination, hook spreading fingers, a rotatable cam for spreading the fingers, a vibrating actuator 157 movable through a uniform path, and a transmission devices 150 adjustable so as to be acted upon by the actuator at different points in its 80 path, whereby the operation of the spreading fingers is varied.

154. A machine for setting simultaneously a plurality of fasteners, having in combination, a driving shaft, punches and mechanism whereby the punches are caused to operate during a part of a revolution by the main shaft, setting devices, and mechanism whereby the setting devices are caused to operate during the remaining part of a revolution by the main shaft, and means for automatically stopping the main shaft after each operation.

155. A machine of the class described, having, in combination, a main shaft, punching and setting instrumentalities, and co-operating work-presenting and fastener-presenting means actuated by said shaft, together with a clutch mechanism for automatically stopping said main shaft after one 95 third and after one complete revolution.

156. A machine of the class described having, in combination, setting dies, hook delivering means, a plate for receiving hooks, and a hook engaging member mounted for reciprocation transversely of said plate and being constructed to permit relative longitudinal shifting of a hook but to move the hook relative to said plate.

157. A machine of the class described, having in combination, setting dies, a carrier for fasteners, a raceway leading to said carrier, means for transferring a series of fasteners from the raceway to the carrier, and members constructed and arranged to engage the fasteners so transferred and subsequently move them into alinement with said setting dies.

158. A machine of the class described, having in combination, a plurality of spaced upsetting dies, a carrier for lacing hooks, a raceway leading to said carrier, a transferring device for moving a series of hooks from the raceway to the carrier, and hook engaging fingers arranged to engage the 120 heads of the hooks so transferred without disturbing their position on the carrier and then spread the hooks into alinement with said upsetting dies.

159. A machine of the class described,

- 5 having in combination, setting dies, a reciprocating head, an anvil mounted thereon for transverse movement, and fastener engaging fingers disposed in said head and arranged to position the fasteners in alinement with the setting dies and then hold them in position during the setting operation, said anvil being moved transversely from said fingers to release the clenched fasteners after 10 the setting operation.
160. A machine of the class described, having in combination, an anvil, a raceway leading thereto, a magazine for supplying fasteners to said raceway, means for separating a series of fasteners from those on the raceway, and means for engaging and feeding the series of fasteners so separated longitudinally along the raceway and to said anvil.
161. A machine of the class described, having in combination, a carrier having a hook setting plate thereon, a raceway leading to said plate, a magazine for supplying fasteners to said raceway, means for separating a series of fasteners from those on the raceway, and a movable brush for engaging each of the fasteners so separated and feeding them longitudinally along the raceway to said plate.
162. A gang fastener setting machine having, in combination, a gang of punches, a coöperating table having a plane face for supporting the work and being movable to force the work on the punches, and a corresponding gang of setting dies arranged with their ends projecting and in alinement with the punches so that the punched work may be threaded upon their ends preparatory to the setting operation.
163. A hook setting machine of the nature described having, in combination, a series of die members arranged in a line and so mounted as to permit of adjusting movement toward or from each other combined with movements in directions at substantially right angles to their line, means operating simultaneously on said members for effecting said combined movements, and co-operating hook setting means.
164. A hook setting machine of the nature described having, in combination, a series of die members arranged side by side in a line, means for holding said members in place but permitting adjusting movements of the members toward and from each other and permitting also combined therewith movements in a direction at approximately right angles to the general line connecting their centers, means for effecting said combined movements, and coöperating hook setting means movable toward said die members to effect the setting operation.
165. A hook setting machine of the nature described having, in combination, a series of die members arranged in a line and capable of movements toward and from each other combined with movements in directions at right angles to the line connecting their centers, adjusting means connected to the die members for effecting said movements, and means for presenting hooks to said die members in all adjusted positions thereof.
166. A hook setting machine of the nature described comprising a series of laterally extending dies mounted for movement to adjust said dies to the conformation, approximately, of various shoe uppers, means operating simultaneously on all of said dies for effecting such adjustment, and hook setting devices coöperating with said dies.

In testimony whereof I have signed my name to this specification in the presence of two subscribing witnesses.

ALBERT LATHAM.

Witnesses:

HERBERT W. KENWAY,
ARTHUR H. RUSSELL.

It is hereby certified that in Letters Patent No. 1,207,057, granted December 5, 1916, upon the application of Albert Latham, of Beverly, Massachusetts, for an improvement in "Machines for Setting Lacing-Hooks and the like," errors appear in the printed specification requiring correction as follows: Page 5, line 109, for the word "if" read *of*; page 11, line 81, claim 10, for the words "power actuated operator" read *power operated actuator*; page 21, line 79, claim 153, for the word "devices" read *device*; and that the said Letters Patent should be read with these corrections therein, that the same may conform to the record of the case in the Patent Office.

Signed and sealed this 10th day of April, A. D., 1917.

[SEAL.]

F. W. H. CLAY,

Acting Commissioner of Patents.

CL 218-0.5.
